(Cl. D74—1)

To all whom it may concern:

Be it known that I, Jeanette Elmyre Coté, a citizen of Canada and a resident of Washington, D. C., have invented a new, original, and ornamental Design for a Combined Pencil Holder, Sharpener, and Stationery Accessories Container, of which the following is a specification, reference being had to the accompanying drawing, forming a part thereof.

In the drawing:

Fig. 1 is a front perspective view of a combined pencil holder, sharpener, and stationery accessories container showing my new design;

Fig. 2 is a top plan view; and

Fig. 3 is a front elevational view thereof.

I claim:

The ornamental design for a combined pencil holder, sharpener, and stationery accessories container, substantially as shown.
